CLAIM

The ornamental design for an aircraft body, as shown and described.

DESCRIPTION

FIG. 1 is a top, front, and left side perspective view of an aircraft body;

FIG. 2 is a bottom, rear, and left side perspective view thereof;

FIG. 3 is a top, front, and left side perspective view thereof;

FIG. 4 is a top, rear, and right side perspective view thereof;

FIG. 5 is a bottom, rear, and right side perspective view thereof;

FIG. 6 is a bottom, front, and right side perspective view thereof;

FIG. 7 is a front elevational view thereof;

FIG. 8 is a rear elevational view thereof;

FIG. 9 is a right side elevational view thereof;

FIG. 10 is a left side elevation view thereof;

FIG. 11 is a top plan view thereof; and,

FIG. 12 is a bottom plan view thereof.

The broken lines portions of FIGS. 1 and 2 are included to show the environment in which the design is embodied and form no part of the claimed design.

1 Claim, 6 Drawing Sheets
